UNITED STATES PATENT OFFICE.

WILLIAM ROSSER, OF CLEVELAND, OHIO, ASSIGNOR TO THE CLEVELAND DENTAL MANUFACTURING COMPANY, OF CLEVELAND, OHIO, A CORPORATION OF OHIO.

DESIGN FOR A DENTAL MALLET.

Application filed April 3, 1922. Serial No. 1,515. Term of patent 7 years.

To all whom it may concern:

Be it known that I, WILLIAM ROSSER, a citizen of the United States, residing at Cleveland, in the county of Cuyahoga, State of Ohio, have invented a new, original, and ornamental Design for a Dental Mallet, of which the following is a specification, reference being had to the accompanying drawing, forming a part thereof.

In said drawing, Fig. 1 is an elevation; Fig. 2 is an end view; and Fig. 3 is a transverse sectional view along the line 3—3 of Fig. 1.

I claim:

The ornamental design for a dental mallet substantially as shown.

WILLIAM ROSSER.
